UNITED STATES PATENT OFFICE.

SAMUEL A. WORCESTER, JAMES L. BRUCE, AND LEROY S. FARNHAM, OF BUTTE,
MONTANA.

MINE CAR.

Application filed May 15, 1922. Serial No. 561,003.

To all whom it may concern:

Be it known that we, SAMUEL A. WORCESTER, JAMES L. BRUCE, and LEROY S. FARNHAM, citizens of the United States, residing 5 at Butte, in the county of Silver Bow and State of Montana, have invented certain new and useful Improvements in Mine Cars; and we do declare the following to be a full, clear, and exact description of the invention, such as will enable others skilled in the art to which it appertains to make and use the same.

This invention relates to improvements in dumping cars and more particularly to 15 those which are primarily used in mines. When the loaded cars are taken from the mine, they are rolled to a comparatively remote point, usually a chute, and there dumped, and one object of the invention is 20 to provide latching means for holding the car body in horizontal position upon the truck, said means being of such a nature that it may be released manually before the car reaches the dumping point, and held in 25 released position so that it will not interfere in any manner with dumping of the body at the proper time. The latching means is usually operated by foot power and when the constructions now commonly 30 used are employed, the latch is not released until the car is to be dumped, no provision being made for holding said latch in released position. The result is that the operator necessarily holds one foot on the 35 latch and stands on the other while over-balancing the car body to dump the same. This is a rather difficult task which can be more easily accomplished by the use of our invention, as the person dumping the body 40 may stand firmly on both feet.

It is well known that the automatic latches heretofore used for holding the outwardly swinging gates or doors of mine cars, often become accidentally released, 45 with the result that the contents of the car body are partially dumped on the track or in the hoisting cage, causing serious wreckage. A further aim of our invention however is to provide a novel association of

parts for positively holding the gate latch 50 against accidental release, provision being made however for releasing the latch-holding means or keeper prior to releasing the gate latch, and provision is preferably made whereby both said latch and said keeper are 55 automatically released when the body is tilted for dumping.

It very often happens that the swinging gates of mine cars are injured by the bumping of one car against another, but another 60 object of our invention is to provide this gate with a bumper which reacts or thrusts against a fixed part of the body. In the preferred form of construction, a bumper is 65 preferably carried by each lower corner of the gate and each bumper contacts with the bottom and one side of the car body, to exert all thrust against these parts instead of having any tendency to injure the gate.

With the foregoing in view, the invention 70 resides in the novel subject matter hereinafter described and claimed, the descriptive matter being supplemented by the accompanying drawings.

Figure 1 is a side elevation of a mine car 75 constructed in accordance with our invention.

Figure 2 is an end elevation showing more 80 particularly the mechanism for latching the car body in horizontal position.

Figure 3 is a detail plan view of the casting by means of which the body is mounted upon the truck.

Figure 4 is a vertical sectional view taken 85 substantially on line 4-4 of Fig. 2.

Figure 5 is a duplicate of Fig. 4 with the exception that it illustrates the latch released and held in released position.

Figure 6 is an end view of the gate end 90 of the car showing more particularly the gate latching means and the bumpers.

Figure 7 is a detail side elevation showing 95 the car in partially dumped position and the gate latching means released.

Figure 8 is a perspective view of the gate latching means.

In the drawings above briefly described, the numeral 1 designates a suitable truck

whose frame is indicated by the reference character 2. Suitably mounted upon this frame is a body 3 which is preferably pivoted at 4 to a casting or bracket 5, the latter being connected with the frame 2 by means of a vertical pivot 6. The pivot 4 comes into play whenever the body 3 is dumped, and the pivot 6 is instrumental in permitting said body to be swung transversely of the truck when it is to be dumped at one side of the latter. Attention may here be directed to the fact that the pivot 4 is nearer to the outlet end of the body than to the other end thereof, so that when the body is loaded and the means released which normally holds it horizontal, said body will still remain in this position until it is dumped by hand. The outlet end of the body 3 is provided with the usual outwardly swinging gate 7, the locking means of which will be hereinafter described fully. The opposite end of the body is provided with a cross-bar 8 which is centrally depressed as indicated at 9 and here rests upon another cross-bar 10 which is secured upon one of the end sills 11 of the frame 2, the ends of said bar 10 being bent upwardly as indicated at 12 to provide a pair of upstanding guide arms which receive the centrally depressed bar portion 9 therebetween. The upper ends of these arms preferably diverge upwardly so as to guide the bar portion 9 between them when the body returns to its normal position after being moved from such position. In the present disclosure, the latch means for holding the body 3 in normal load-carrying position, co-acts with the depressed portion of the bar 8, and is mounted upon the end-sill 11 of the truck frame 2, but it will be understood that this arrangement need not be followed in all instances, even though it has proven to be very practicable.

The numeral 13 designates a vertically disposed latch which is pivoted at 14 to suitable brackets 15 carried by the end-sill 11, the upper end of said latch being provided with a suitable nose 16 to take over the depressed portion 9 of the bar 8, while the lower end of said latch is provided with a foot pedal 17. A spring 18 is preferably provided for maintaining the latch 13 in operative position, and we provide novel means whereby said latch may be held in the released position shown in Fig. 5, whereby it may be released before the dumping point of the car is reached and the body may be dumped by another operator when it arrives at said point. In the preferred form of construction, the latch 13 is provided with a laterally extending projection 19 and a keeper 20 rests normally upon said projection as shown in Figs. 1 and 4, said keeper being preferably in the form of an arm passing through an opening 21 in the end-sill 11 and pivoted at 22 to suitable brackets carried by said sill.

The moment the latch 13 is moved into the position shown in Fig. 5, so as to release it from engagement with the body, the keeper 20 drops by gravity behind the projection 19 as shown in said last named figure, the result being that the latch 13 is held released so that the body may be subsequently dumped.

Means are provided to automatically release the keeper 20 from operative engagement with the projection 19, as soon as the dumping operation of the body takes place, and in the present showing, this means includes a coiled compression spring 23 and a push-rod 24 rising therefrom, said spring 23 being held against upward projection when the body 3 is in horizontal position, by means of said rod which is depressed by a suitable part of the body. We prefer that the rod 24 shall pass slidably through openings 25 formed in the upper and lower flanges of the sill 11 and in the cross bar 10. Also we prefer that this rod shall pass through the coil spring 23 and through a slot 26 in the keeper 20. The rod in question is provided with a nut and lock-nut 27 so that the tension of the spring 23 may be varied as occasion may require and when the latch 13 is released and the keeper 20 dropped by gravity as shown in Fig. 5, said keeper then rests upon the uppermost of the nuts 27, the rod 24 being now held in depressed position by contact of the bar portion 9 with the upper end of the push-rod 24. With the parts set in this position, (see Fig. 5) the body is in readiness for dumping when the proper point is reached. When said body is tilted, the bar portion 9 moves upwardly from the rod 24, with the result that the spring 23 immediately acts to thrust said rod upwardly, thereby releasing the keeper 20 from engagement with the projection 19 and allowing the spring 18 to pull the latch 13 inwardly to the position shown in Fig. 4. After dumping the body, the latter returns to its normal position and the portion 9 of the bar 8 strikes the beveled nose 16 of the latch 13, whereupon said latch yields outwardly until said portion 9 rests upon the bar 10. As soon as this takes place, the spring 18 moves the latch to operative position. Attention may here be directed to the fact that during the outward movement of the latch 13, incident to return of the body to normal position, it does not move far enough to permit the keeper 20 to drop behind the projection 19. The preferred form of gate latching means is illustrated and includes a substantially horizontal latch 30 pivotally mounted between its ends at 31 upon a pair of supporting plates 32 which are secured to and extend downwardly from the body 3 adjacent the gate-carrying end of said body. The outer end of the latch 30 is provided

with a beveled nose 33 receivable in an opening 34 in the latch plate 35 which depends from the gate 7. A coiled spring 36 is preferably connected with the inner end of the latch and acts to normally move the same into effective latching engagement with the latch plate 35. Other means however may be employed if desired to move this latch to operative engagement.

10 For automatically releasing the latch 30 when the body 3 tilts for dumping, we provide an operating bar 37 extending longitudinally beneath one end of the body 3 and pivoted at 38 to the bracket 5, the pivot being located at a point eccentric with respect to the pivot 4 of the body 3. The result is that when the body dumps, the body and the bar 37 move relatively and this movement is utilized to release the latch. The 20 outer end of the bar 37 preferably turns downwardly as indicated at 39 for co-action with an inclined cam 40 on the upper edge of the latch 30 (see more particularly Figs. 1, 7 and 8). Normally, that is when the 25 body 3 is horizontal and the gate 7 is closed, the latch 30 and bar 37 are related in the manner shown in Fig. 1, but when relative movement of the body 3 and said bar takes place, the end 39 of the latter acts upon the cam 40 as shown in Fig. 7, thereby releasing the latch 30 and permitting the door 7 to swing outwardly by gravity and the action of the load.

To prevent any possibility of the latch 30 becoming accidentally released from engagement with the latch plate 35, we provide a suitable keeper or keepers, two hooks 41 being shown for this purpose. These hooks are pivoted at their upper ends to the latch 30 as indicated at 42 and the lower or bill-carrying ends of said hooks are adapted to take under the lower edge of the latch plate 35 as shown in Fig. 1, whereby there is no possibility of the outer end of the latch moving upwardly and disengaging the nose 33 from said plate. Means are provided for automatically releasing the keepers or hooks 41 prior to release of the latch 30, when dumping of the body 3 takes place. In the 50 present showing, a link 43 is pivoted at one end to the lower ends of the hooks 41 and is pivoted at its other end to the lower ends of a pair of upstanding links 44, the upper ends of the latter being pivoted at 45 to the plate 32. The bar end 39 is provided with one or more rigid depending arms 46 provided with outstanding pins or the like 47 to engage the links 44. While the pin or pins 47 do not interfere with slight inward swinging of the 55 keepers 41 against the tension of their holding spring 48 when the door 7 is pushed to closed position and the latch 30 is consequently raised, it will be seen that when the bar 37 moves inwardly with respect to the 60 body during dumping of the latter, said

pin 47 will first pull upon the link 44, thereby causing link 43 to release the keepers 41 from engagement with the latch plate 35. Further inward movement of bar 37 with respect to the body 3, causes the bar end 39 70 to coact with the cam 40 and release the latch 30, thereby permitting the door 7 to swing outwardly for discharging the contents of said body. When this body is returned to its normal position by hand, the 75 latch 13 automatically locks it upon the truck and the gate 7 closes by gravity. If the gate should fail to latch, it is simply necessary to push the same inwardly, whereupon the latch 30 will yield against the action of its 80 spring 36 until the nose 33 passes completely through the opening 34. When this occurs, the spring 36 moves the latch to effective position and at the same time the spring 48 moves the keepers 41 into engagement with 85 the latch plate, whereby to prevent the latch from becoming released accidentally.

During passage of the cars along the track, it often happens that they bump into each other with such force as to be injurious to the gates 7. In order to prevent this occurrence, we provide a bumper carried by the gate of each car, said bumper being arranged to re-act against a solid part of the car body instead of only against the gate. In the 90 present showing, we have provided each lower corner of the gate 7 with an inclined bumper bar 50, the ends of said bar being projected beyond the edges of the gate so that they may strike the bottom of the body 95 3 and the adjacent side wall thereof. Thus, when the bumpers 50 come up against an adjacent car, instead of having a tendency to injure the gate 7, they thrust against the side and bottom of the car and do not injure the latter in any manner.

From the foregoing, the construction and operation of our improved dumping car will probably be understood, but it may be well to add a brief explanation, giving its 100 operation. Assuming that the car is loaded, it of course stands in the horizontal position depicted in Fig. 1, the latch 13 being then in operative position to hold the body 3 against dumping, while the latch 30 is active 105 to lock the gate 7, being held against accidental release during rolling along the track, by means of the keeper or keepers 41. When the car nears the point at which it is to be dumped, an attendant presses upon the 110 foot pedal 17 of the latch 13, thereby moving said latch from engagement with the car body as shown in Fig. 5, whereupon the keeper 20 drops by gravity behind the projection 19 and holds said latch in released 115 position while the car continues to the dumping point. When this point is reached, the car is manually dumped and due to the fact that the operator at this point does not have to release the latch and hold it released 120 125 130

with one foot, he may stand firmly upon both feet while overbalancing the body and dumping it. The moment the body tilts sufficiently to disengage the push rod 24, spring 23 is allowed to expand upwardly, with the result that the keeper 20 is released from the projection 19 and the spring 18 returns the latch 13 into position to again lock the car body when the latter returns to 10 horizontal position. As soon as tilting of the body starts, relative movement of said body and bar 37 take place, the result being that the pins 47 pull upon the links 44 and 43, thereby releasing the keepers 41 from engagement with the latch plate 35. Further relative movement of the bar 37 and body 3 causes the end 39 of said bar to co-act with the cam 40 and release the latch 30 as shown in Fig. 7, thereby permitting the gate 20 7 to swing outwardly. As the body returns to horizontal after dumping the load, the gate 7 closes by gravity and engages with the latch 30 and the body also engages the latch 13, so that the car is in 25 readiness to receive another load when it is returned to the mine. If from any cause, the gate should not latch when the body returns to horizontal, it is simply necessary to push said gate inwardly, whereupon it 30 will operatively engage its holding means 30—41. Similarly, though barely possible, that the bar portion 9 should not operatively engage with the latch 13, if this should occur, a downward pull on the body will suffice to overcome the difficulty.

Our invention is comparatively simple and inexpensive, yet is much more efficient and reliable than a number of arrangements now commonly used upon mine cars and while the 40 details of construction herein disclosed have proven very effective, we do not wish to be restricted to these details otherwise than set forth in the appended claims. Furthermore, while we have described our invention for 45 use as a mine car, it will be obvious that dumping cars and trucks of all sorts could be equipped with our device if desired.

We claim:

1. The combination with a dumping body 50 having an outwardly swinging gate; of latch means for said gate, means for holding said latch means against accidental release, and means for successively releasing said holding means and said latch means.
2. The combination with a dumping body 55 having an outwardly swinging gate; of latch means for said gate, means for holding said latch means against accidental release, and means for automatically releasing said holding means and said latch means successively 60 when the body is tilted for dumping.
3. The combination with a dumping body 65 having an outwardly swinging gate, and a truck on which said body is pivoted; of latch means for said gate, means for holding

said latch means against accidental release, and means for successively releasing said latch means and said holding means, including an operating member connected with the truck at a point eccentric with respect to the 70 pivot of said body.

4. The combination with a dumping body having an outwardly swinging gate provided with a latch plate; of a vertically movable latch mounted on said body for engagement 75 with said latch plate, a keeper carried by said latch to engage said latch plate and prevent accidental release of said latch, and means for automatically releasing said keeper and said latch successively when the 80 body dumps.

5. The combination with a dumping body having an outwardly swinging gate provided with a latch plate; of a vertically movable latch mounted on said body for engagement 85 with said latch plate, a keeper pivoted to and depending from said latch to engage the lower edge of said latch plate and hold said latch against accidental release, and means for automatically releasing said keeper and 90 said latch successively when the body dumps.

6. In a dumping car, a truck, a dumping body mounted pivotally thereon and having an outwardly swinging gate provided with a depending latch plate, a latch under the 95 car body pivoted thereto for coaction with said latch plate, a bar extending longitudinally under said body and connected with the truck at a point eccentric with respect to the pivot of the body, said bar being associated with said latch for releasing it when the bar and body move relatively during load dumping, a keeper pivoted to and depending from said latch to prevent accidental release thereof by engagement with 100 said latch plate, a link pivoted to and depending from said body, a connection between said link and keeper, and a rigid arm depending from said bar and engaged with said link for bodily moving the latter and 105 releasing said keeper prior to release of the latch.

7. The combination with a dumping body having an outwardly swinging gate, and a truck on which said body is pivoted; of a 110 latch for said door, and releasing means for said latch, including an operating bar connected with the truck at a point eccentric with respect to the pivot of the body.

8. The combination with a dumping body 115 having an outwardly swinging gate, and a truck on which said body is pivoted; of a latch for said door mounted on said body, a bar extending longitudinally beneath the body and connected with the truck at a 120 point eccentric with respect to the pivot of said body, and a cam associated with said bar and latch for releasing the latter when the body and said bar move relatively while 125 dumping the body.

9. The combination with a dumping body having an outwardly swinging gate, and a truck on which said body is pivoted; of a latch for said door mounted under said body and having a cam, and a latch-releasing bar extending longitudinally under the body and cooperable with said cam to release the latch, said bar being pivoted to the truck at a point eccentric with respect to the pivot of said body. 10
- In testimony whereof we have hereunto set our hands.
